US00D470990S

(12) **United States Design Patent** (10) Patent No.: **US D470,990 S**
 Han et al. (45) Date of Patent: ** Feb. 25, 2003

(54) **GLOBAL TRUCK**

(75) Inventors: **Chul Hwan Han**, Changwon (KR);
Young Hwan Cha, Changwon (KR);
Taek Woo Lee, Kyungnam (KR)

(73) Assignee: **Clark Material Handling Asia Co., Ltd.** (KR)

(**) Term: **14 Years**

(21) Appl. No.: **29/152,354**

(22) Filed: **Dec. 13, 2001**

(30) **Foreign Application Priority Data**

Jul. 20, 2001 (KR) 2001-20118

(51) LOC (7) Cl. **12-05**

(52) U.S. Cl. **D34/34**

(57) **CLAIM**

The ornamental design for a global truck, as shown and described.

DESCRIPTION

FIG. 1 is a perspective view of a global truck according to my new design;

FIG. 2 is a front view of a global truck according to my new design;

FIG. 3 is a rear view of a global truck according to my new design;

FIG. 4 is a left side view of a global truck according to my new design;

FIG. 5 is a right side view of a global truck according to my new design;

FIG. 6 is a plan view of a global truck according to my new design;

FIG. 7 is a bottom view of a global truck according to my new design; and,

FIG. 8 is an exemplary drawing view of a global truck according to my new design.

The broken line showing of a box in FIG. 8 is for illustrative purposes only and forms no part of the claimed design.
